US00D503161S

(12) **United States Design Patent** (10) Patent No.: **US D503,161 S**
(45) Date of Patent: **** Mar. 22, 2005**

(54) **DVD PLAYER**

(75) Inventors: **Hartmut Heinrich Esslinger**, Sunnyvale, CA (US); **Chris Green**, Sunnyvale, CA (US); **Howard Geoffrey Nuk**, Sunnyvale, CA (US); **Nico Michler**, Sunnyvale, CA (US); **Peter Kossev**, Sunnyvale, CA (US); **Jon Christopher Lake**, Sunnyvale, CA (US)

(73) Assignee: **Disney Enterprises, Inc.**, Burbank, CA (US)

(**) Term: **14 Years**

(21) Appl. No.: **29/160,144**

(22) Filed: **May 3, 2002**

(51) LOC (7) Cl. **14-01**

(52) U.S. Cl. **D14/136**

(58) Field of Search **D14/135-136, D14/156-157, 160-164, 167-168, 188, 193-198, 257-258; 369/6-7, 75.1, 75.2, 77.1, 77.2; 455/344, 347, 350-351**
